UNITED STATES PATENT OFFICE.

WILLIAM McCLOVE, OF SCRANTON, PENNSYLVANIA.

FURNACE WITH AIR, STEAM, AND HYDROCARBON FUEL FEEDING ATTACHMENTS.

SPECIFICATION forming part of Letters Patent No. 497,194, dated May 9, 1893.

Application filed December 24, 1892. Serial No. 456,261. (No model.)

To all whom it may concern:

Be it known that I, WILLIAM McCLOVE, a citizen of the United States, residing at Scranton, in the county of Lackawanna and State 5 of Pennsylvania, have invented certain new and useful Improvements in Furnaces with Air, Steam, and Hydrocarbon Fuel Feeding Attachments; and I do hereby declare the following to be a full, clear, and exact description 10 of the invention, such as will enable others skilled in the art to which it appertains to make and use the same.

My invention consists in a combination with a boiler or other furnace and a liquid 15 hydrocarbon source of supply, as, for instance, a tank, of novel means, as will be herein-after described, whereby, by the pressure of live steam and the condensed water thereof, the supply of liquid hydrocarbon is forced 20 out of the source of supply or tank into a mixing live steam branch pipe of the steam supply pipe, and said liquid hydrocarbon mixed with the live steam in said branch pipe, and the mixture forced into a circulating vaporizing coil or chamber, and steam superheated 25 and the hydrocarbon vaporized; and from said steam superheating and vaporizing coil or chamber, the hydrocarbon is forced by the live steam to the air duct of a blower, and 30 this mixture mixed with air in the air duct of the blower, and thence introduced beneath and up through a mass of solid carbonaceous fuel on a grate or fire bed of a furnace, and this compound blast of air, superheated steam 35 and hydrocarbon vapor thus utilized as an auxiliary fuel.

My invention also consists in a combination of pipes and cocks, as will be herein-after described, whereby, at will, either hydrocarbon 40 unmixed with steam can be fed out of the tank into the vaporizing coil or chamber by pressure of live steam from the boiler, and condensed water thereof; or the liquid hydrocarbon mixed with live steam can be introduced into a steam superheating and liquid 45 hydrocarbon vaporizing coil or chamber, and thence passed in a mixed condition to the air duct of the blower and there mixed with air and passed beneath and up through a mass of 50 solid carbonaceous fuel on a grate or supporting bed of the furnace, and thus utilized as an auxiliary fuel.

In the accompanying drawings, Figure 1 represents my invention and a boiler furnace

in side elevation. Fig. 2 is a cross section 55 showing the boiler furnace in section and my invention in front elevation. Figs. 3 and 4 are similar views to Figs. 1 and 2, but showing the invention as adapted for passing only the liquid hydrocarbon into the vaporizer, 60 vaporizing it and from thence passing the vapor into a steam pipe and thence into a branch pipe wherein it is mixed with steam, and the mixture passed to the air duct and there mixed with air and passed beneath and up 65 through the solid carbonaceous fuel supporting bed of a furnace.

A in the drawings designate side walls; B, a bridge wall; C an ash pit; D a grate or other appropriate fuel supporting bed; E a 70 steam boiler; F a steam blower of a boiler furnace of ordinary construction. The blower in the illustration given consists of a duct or tuyere F' and steam jetting device G connected with a steam pipe H leading from the 75 boiler E; but the discharging portion H⁴ of the steam pipe H may be entered into the duct of a fan blower as illustrated in Fig. 3 of Letters Patent No. 485,820, granted to me November 8, 1892, or in any other practical way, 80 whereby a mixture of air, steam and vapor of liquid hydrocarbon can be forced into the ash pit or underneath and up into a mass of solid 85 carbonaceous fuel on a grate or other appropriate fuel supporting bed; or into any other suitable part of a boiler furnace and utilized as an auxiliary fuel for facilitating and promoting combustion.

In the drawings I have shown a mechanism comprising a tank I, water chamber a, pipe I⁶ 90 with cock I⁷, the filling means I' with cock I², or the filling means I³ with cock I⁴, the liquid hydrocarbon conducting pipes K, K', K² and the globe valve M and the vaporizing coil or chamber J and jet nozzle d, but the construction and arrangement of the parts are the same as in my application for a patent filed December 22, 1892, Serial No. 456,023, and claimed in said application, and therefore need not be described herein more particularly. So, too, is the construction of the steam pipe H, its branches H', H², H³, H⁴, H⁵, H⁶, H⁷, globe valves L and N, and drip cock or valve s the same as in my aforesaid application for a patent, and claimed in said application, and therefore need not to be described herein more 100 particularly. 105

In connection with the construction and

arrangement of parts shown and described in my aforesaid application or any other suitable means adapted for supplying steam and hydrocarbon to the apparatus, two horizontal transverse pipes O O', each provided with a globe cock O², O³, are employed for connecting the pipe H⁴ with the circulating steam superheating and hydrocarbon vaporizing coil or chamber J; also a vertical pipe O⁵ provided with a globe valve O⁶ is provided for connecting the vertical portions of the pipe K above and below the vaporizing coil or chamber J; and globe valves O⁷, O⁸, are provided on said portions of the pipe K. A globe valve O⁴ is also provided on the mixing pipe H⁴ between the horizontal transverse pipes O, O'. With this arrangement, it will be seen that when the globe valves L, M and N, and O², O³ and O⁶, are opened, the liquid hydrocarbon and steam being thus allowed to circulate, the operation is as follows: The steam passing from pipe H along pipes H⁸, H⁵, H⁶, and H⁷ enters the water chamber a beneath the liquid hydrocarbon in tank I, and forces the liquid hydrocarbon out of the tank into the pipes K K', O⁵, K² and through discharging nozzle d into live mixing branch pipe H⁴ where it is mixed with the live steam, and then the mixture passes into a cross pipe O and thence into the liquid steam superheating and liquid hydrocarbon vaporizing coil or chamber, and through cross pipe O' into the lower end of pipe H⁴ leading to air duct of blower. If it is desired to have simply the liquid hydrocarbon pass through the vaporizing coil or chamber the cocks L, M and N, O⁸, O⁴ and O⁷ are opened, and the cocks O², O³, O⁶ are closed; and the operation is as follows: The liquid hydrocarbon supplied from the tank as before described passes through pipe K into the vaporizing chamber or coil, and therefrom through branch K² into nozzle d, and into the live steam mixing pipe H⁴ and therefrom the mixture passes to the air duct of the blower. In the event that the supply of hydrocarbon becomes exhausted and it is not convenient to immediately refill the tank I, the valves M, N, O², O³ and O⁸ are closed, the valves O⁴ and L being already opened, and the operation is as follows: The steam passes directly through pipes H, H² and H³ into the pipe H⁴ and thence to air duct of the blower where the steam mixes with air, and the mixture passes to the fire when the cock M is used on the apparatus.

Instead of manipulating all of the cocks mentioned to effect the last mentioned operation, the cock O⁷ might remain open, as cocks M and O³ being closed would prevent any steam from passing into the vaporizing coil or chamber.

In Figs. 3 and 4, a slightly different construction and arrangement of pipes and vaporizing coil or chamber to that shown in Figs. 1 and 2, is shown, whereby the liquid hydrocarbon mixed with live steam is passed through the mixing live steam pipe, thence to the

steam superheating and hydrocarbon vaporizing coil or chamber, and thence to the air duct of the blower. In this arrangement, a pipe R and three cocks R', R², R³ are provided as shown, and on opening the cocks L, M and N and R', R², and closing cock R³, the steam and hydrocarbon will flow through the mixing branch pipe H⁴ into the steam superheating and hydrocarbon vaporizing coil or chamber, thence into the air duct of the blower. In the event of the liquid hydrocarbon becoming exhausted in tank I, steam alone can be passed directly to the blower duct by closing cocks M, R', R² and opening cock R³, whereupon the steam will pass directly to the air duct of the blower.

As the cock M is simply provided as an additional regulator to the flow of the liquid hydrocarbon, its provision is not absolutely essential to the working of the apparatus, as the flow of liquid hydrocarbon can be regulated by the cock N by regulating the pressure from the steam supply. The cock M, may, therefore, be dispensed with.

What I claim as my invention is—

1. In a furnace, the combination of a live steam pipe H from a boiler or other source of steam supply, a liquid hydrocarbon conducting pipe K connected with a source of supply, a circulating heating coil or chamber J, a pipe R connected with the steam supply pipe H, a branch trap H² connected with the steam supply pipe and with a live steam branch pipe H⁴ of the steam supply pipe, cocks R', R² and R³ applied respectively to the branch H², to a branch between the circulating heating coil or chamber J and to branch R, and also to the branch R between the branch H² and the cock R²; and valves or cocks L and N, the cock L being on the steam pipe H and the cock N suitably located on branch of supply steam pipe, substantially as described.

2. In a furnace the combination of a steam supply pipe from a boiler or other source of steam supply, a liquid hydrocarbon conducting pipe connected to a source of supply, a circulating heating coil or chamber connected with the hydrocarbon conducting pipe and with the steam supply pipe, the pipes O, O', O⁵, the pipes O and O' being connected with the circulating heating coil and the pipe H⁴, at points above and below the cock O⁴, and the one O⁵ to the hydrocarbon conducting pipe K and its branch K² at points above and below the cocks O⁷, O⁸, and globe valves or cocks O², O³, O⁴, O⁶, on pipes O, O', H⁴, O⁵, and valves or cocks L, N, the valve L being on the steam supply pipe and the valve N suitably located on branch of supply steam pipe, substantially as described.

In testimony whereof I hereunto affix my signature in presence of two witnesses.

WILLIAM MCCLAVE.
